(57) **CLAIM**

The ornamental design for a lantern, as shown and described.

DESCRIPTION

FIG. 1 is a top perspective view of a first version of a lantern showing the new design;

FIG. 2 is a bottom perspective view thereof;

FIG. 3 is a first side view thereof;

FIG. 4 is a second side view thereof;

FIG. 5 is a third side view thereof;

FIG. 6 is a fourth side view thereof;

FIG. 7 is a top view thereof; and

FIG. 8 is a bottom view thereof.

FIG. 9 is a top perspective view of a second version of a lantern showing the new design;

FIG. 10 is a bottom perspective view thereof;

FIG. 11 is a first side view thereof;

FIG. 12 is a second side view thereof;

FIG. 13 is a third side view thereof;

FIG. 14 is a fourth side view thereof;

FIG. 15 is a top view thereof; and,

FIG. 16 is a bottom view thereof.

The dashed lines shown in FIGS. 1-8 illustrate portions of the lantern that form no part of the claimed design.

1 Claim, 14 Drawing Sheets
